UNITED STATES PATENT OFFICE.

RICHARD BRADLEY, OF SWANSEA, ARIZONA.

HAT.

1,338,283.

Specification of Letters Patent. Patented Apr. 27, 1920.

Application filed July 16, 1919. Serial No. 311,353.

To all whom it may concern:

Be it known that I, RICHARD BRADLEY, a citizen of the United States, residing at Swansea, in the county of Yuma and State 5 of Arizona, have invented a new and useful Hat, of which the following is a specification.

It is the object of this invention to provide a novel means whereby, at the will of 10 an operator, a hat or other article of head-wear may be ventilated, the construction being such that rain or snow cannot find its way within the crown of a hat.

It is within the province of the disclosure 15 to improve generally and to enhance the utility of devices of that type to which the invention appertains.

With the above and other objects in view, which will appear as the description 20 proceeds, the invention resides in the combination and arrangement of parts and in the details of construction hereinafter described and claimed, it being understood that, within the scope of what is claimed, changes 25 in the precise embodiment of the invention shown can be made without departing from the spirit of the invention.

In the accompanying drawings:—

Figure 1 shows in side elevation, a hat 30 embodying the invention, parts being broken away; Fig. 2 is a section on the line 2—2 of Fig. 1; Fig. 3 is a section on the line 3—3 of Fig. 1.

There is shown in the drawings, a hat 35 comprising a crown 1 and a brim 2, the hat being surrounded, if desired, by the usual trimming band 3. At spaced points, the crown 1 is struck outwardly to form ventilating openings 4 and to form semi-conical guards 5 for the openings, the guards, obviously preventing snow or rain from finding its way into the openings. Located 40 within the crown 1 is a sweat band 6, disposed in operative relation to the guards 5. The sweat band 6 is connected to the crown 1 by separable fasteners 8, 9, 10 and 11, the fasteners 9—11 being disposed opposite to each other and a corresponding relation existing between the fasteners 8 and 9. The 45 fasteners may be snap structures including a part carried by the crown 1 and a part carried by the sweat band 6.

When the sweat band 6 is arranged as shown in Figs. 1 and 3, openings or per-

forations 7 in the sweat band coöperate with 55 the guards 5 and the openings 4 and afford ventilation, it being impossible for rain or snow to find its way within the crown. The members of the fasteners 8 and 10, for instance, may be detached from each other. 60 Then the sweat band may be reversed on an axis passing through the fasteners 9 and 11. When the sweat band is reversed, as aforesaid, the imperforate portions of the sweat band lie adjacent to the openings 4 65 and the guards 5, no air under such circumstances finding its way into the crown. The construction of the device is such, that the wearer, at will, may be provided with a ventilated hat, or with one which is not 70 ventilated.

Having thus described the invention, what is claimed is:—

1. A hat comprising a crown and a sweat band having ventilating openings; and 75 means for pivoting the band to the crown at spaced points, the band being reversible on an axis passing said points to bring the openings of the band and the crown into and out of registration. 80

2. A hat comprising a crown and a sweat band having ventilating openings; means for pivoting the band to the crown at spaced points, the band being reversible on an axis passing through said points to bring the 85 openings of the band and the crown into and out of registration; and means for locking the sweat band against pivotal movement.

3. A device of the class described, constructed as set forth in claim 1 and further characterized by the fact that the crown is struck outwardly to define a guard for the ventilating opening in the crown. 90

4. A device of the class described, constructed as set forth in claim 2, and further characterized by the fact that both the means for pivoting the band to the crown and the means for locking the band to the crown consist of separable fasteners. 95

In testimony that I claim the foregoing as my own, I have hereto affixed my signature in the presence of two witnesses.

RICHARD BRADLEY.
